UNITED STATES PATENT OFFICE.

OTTO H. DE LAPOTTERIE, OF KENT, OHIO, ASSIGNOR TO THE LAMSON & SESSIONS COMPANY, OF CLEVELAND, OHIO, A CORPORATION OF OHIO.

RIVET.

Application filed April 2, 1924. Serial No. 703,763.

To all whom it may concern:

Be it known that I, Otto H. DE LAPOTTERIE, a citizen of the United States, residing at Kent, in the county of Portage and State of Ohio, have invented certain new and useful Improvements in Rivets, of which the following is a specification.

This invention relates to an improvement in rivets having a partly formed end or head.

The invention is shown in the accompanying description and in the drawings in which:

Figs. 1 and 2 are respectively an elevation and a plan of the new rivet;

Figs. 3 and 4 are diagrammatic cross sections showing the rivets before and after being driven, the rivets having round heads;

Figs. 5 and 6 show diagrammatically the formation of cone and steeple-head rivets;

Fig. 7 shows a modified form of head; and

Fig. 8 shows the manner in which the heads are formed.

The characteristic feature of my invention is the formation on the shank of an enlarged head which is of greatest diameter at about its median portion. Beneath this median portion which is of greater diameter than the shank, the head has a concave portion merging into the cylindrical shank; and above the median portion the head is formed with a similar concave portion extending to an upper end-portion, which is of about the same diameter as the shank, but may be slightly smaller. The top of the rivet is preferably formed with a rounded or spherical surface and may be provided with an outwardly extending centrally located nub.

The curvature of the two concaved portions is preferably the same, these surfaces being generated by arcs of the same radius, though this and the other features described may be varied to some extent.

The median portion may be formed as a sharp edge at the meeting of the concave surfaces, but preferably is of some width so that there is produced what may be termed a rib.

This novel form of head for a reformable rivet has been arrived at after long experimentation and makes it possible (1) to cheaply manufacture the rivet without producing such inherent strains that the head may have a tendency to break off after it

has been driven or set by the usual hot method; and (2) to insure that the rivet when set will completely fill the hole through the plates being riveted and will completely engage the surface of the plates and make a tight joint, so that the minimum amount of calking will have to be done.

The heads above described are preferably formed cold, by dies, as shown in Fig. 8, the resulting rivet having the advantages of a truly cylindrical shank, with its end cut square, and with no fins or flashes between the lower surface of the rivet head and the plates.

As shown in Figs. 1 and 2, the rivet has a cylindrical shank 5, the median or ridge portion 2, the rounded top 1, and the concave portions 3 and 4.

In Fig. 3, the rivet is shown as located within the holes of several plates 6, 7 and 8, before being set. In Fig. 4 is shown the finished rivet after riveting pressure has been applied to the tools 9 and 10.

In Figs. 5 and 6, tools adapted to form cone and steeple heads, respectively, are shown, the final form of the head being shown in dotted lines.

Fig. 7 shows a modified form in which an additional nub or projection is formed on the top of the cap.

The head is formed in solid dies, as shown in Fig. 8, where 40 represents the blank cut off from round stock, 11 a stationary die member into which the blank 10 is placed and 12 the heading tool. The orifice in the stationary die flares outwardly near its upper end defining preferably a convex curved surface 11^a and the heading tool or hammer 12 has a recess which is co-axial with the orifice in the stationary die 11 and which has a downwardly and outwardly flaring preferably convex surface 12^a similar to the convex surface 11^a in the orifice.

Assuming that a blank of proper length is used, the head portion resulting from the co-operation of the die 11 and heading tool 12 has the form indicated in Figs. 2 and 3 and the additional nub, as shown in Fig. 7, not being essential.

This head is preferably formed cold, and it has been found that the metal of the blank, under the action of the upwardly and downwardly flaring surfaces of the compression tools flows easily into a compacted head portion without the production of flaws or

strain regions, which might result in the subsequent cracking or breaking off of the head.

If the additional nub is to be formed on the top of the head, a suitable cavity is provided in the tool 12, thereby producing the reformable rivet shown in Fig. 7, this form being particularly desirable in finishing rivets of steeple head form.

10 The shape given to my new reformable rivet, therefore, has the double advantage of easy and accurate manufacture, and of capability of use to make a number of forms of rivet, each of which can be driven with 15 the assurance that a tight joint will be effected.

In setting the rivets, which is effected in the usual manner, the pressure of the rivet-setting tools is applied axially of the rivet. 20 This causes the shank to expand within and fill the hole, while the metal of the head is displaced along easy lines of flow not at right angles to the axis, and because of the interspace between the wall of the heading 25 tool and the concave upper portion of the head, the displaced metal can flow before it comes into contact with the wall, with the result that the metal of the head is finally compacted into the desired shape and forced 30 against the plate, without the formation of fins or flashes between the bottom of the head and the plate.

While obviously variations in the diameter of the head portion relative to the diameter of the shank, and in the radius of curvature of the concave portions may be made, without departing from my invention, the general relations between the various size factors should be preserved. As 40 a guide for this purpose, the rivets, as shown in the drawings, have been drawn to scale.

I claim:

1. As an article of manufacture, a rivet comprising a cylindrical shank portion and a head having a median portion of greater 45 diameter than the shank and similar concave portions extending inwardly from said median portion, one of said concave portions merging with the shank portion.

2. As an article of manufacture, a rivet 50 comprising a cylindrical shank portion and a head having a median portion of greater diameter than the shank and similar concave portions extending inwardly from said median portion, one of said concave portions 55 merging with the shank portion, and the other concave portion terminating in a rounded cap portion.

3. As an article of manufacture, a rivet comprising a cylindrical shank portion and a head having a median portion of greater diameter than the shank and similar concave portions extending inwardly from said median portion, one of said concave portions merging with the shank portion, and the 60 other concave portion terminating in a rounded cap portion, the diameter of the base of the cap portion being substantially 65 the same as the shank.

4. As an article of manufacture, a rivet 70 comprising a cylindrical shank portion and a head having a median portion of greater diameter than the shank and similar concave portions extending inwardly from said median portion, one of said concave portions 75 merging with the shank portion, and the other concave portion terminating in a rounded cap portion, said cap portion being provided with a centrally located nub.

In testimony whereof, I affix my signature.

OTTO H. DE LAPOTTERIE.
